**AIR AND LIQUID PRESSURE SPRAY GUN FOR
CLEANING DIESEL ENGINES AND THE LIKE**

Edward Sevander Johnson, Chicago, Ill.

Application December 13, 1957, Serial No. 702,559

2 Claims. (Cl. 239—288)

The present invention relates to air and liquid pressure spray guns for cleaning diesel engines and the like, and is particularly concerned with spray guns which may be employed with sources of air under pressure and water under pressure at such different pressures that the air would ordinarily prevent the flow of the water and cause the water to back up in its supply conduit if a spray gun embodying the present invention were not employed.

One of the objects of the invention is the provision of improved equipment for cleaning diesel engines of locomotives, which are usually covered with grease and dirt after coming in from a railroad run, by means of a detergent solution and a rinsing solution of water, both of which are sprayed by the use of air under pressure, the cleaning occupying a minimum amount of time and labor and material as distinguished from the methods of the prior art.

Another object of the invention is the provision of an improved air and liquid spray gun which may be employed with the usual sources of air pressure available at 60 to 150 pounds pressure, always greater than the water source, which is at 30 to 90 pounds of pressure, and by means of which the flow of air and liquid may be so controlled that either detergent or water may be caused to forcibly impact the engine to be cleaned, the detergent dissolving and loosening the grease and dirt, and the water later impacting the engine parts and driving off any remaining detergent, grease, and dirt, while the use of air with the water leaves the parts clean and dry.

Another object of the invention is the provision of an improved air and liquid spray gun in which the hands of the user are protected against excessive heat and the user is adapted to so adjust the valves for air and for water that the water is atomized and sprayed with the spray of air in a whirling spray, for most effectively drying the cleaned parts.

Another object of the invention is the provision of an improved air and liquid spray gun which is simple in construction, which includes a minimum number of parts, which is adapted to be manufactured economically, which is adjustable for use with widely different liquid and air pressures, and which may be used for a long period of time without necessity for repairing or replacing any of its parts.

Other objects and advantages of the invention will be apparent from the following description and the accompanying drawings, in which similar characters of reference indicate similar parts throughout the several views.

Referring to the two sheets of drawings accompanying the specification,

Fig. 1 is a side elevational view of an air and liquid spray gun embodying the invention;

Fig. 2 is a similar view in partial section, the section being taken on the plane passing through the axis of the nozzle and the axes of the supply pipes;

Fig. 3 is a sectional view taken on the plane of the line 3—3 of Fig. 2, looking in the direction of the arrows;

2

Fig. 4 is a fragmentary view similar to Fig. 2 of the nozzle structure on a larger scale;

Fig. 5 is a fragmentary view in partial section, showing the relation of the inner nozzle cap to the outer nozzle cap, similar to Fig. 4, but with the parts in a different position;

Fig. 6 is a side elevational view of a nozzle plug provided with a valve head, which is utilized in the inner nozzle;

10 Fig. 7 is a fragmentary sectional view, taken on the plane of the line 7—7 of Fig. 2, looking in the direction of the arrows;

Fig. 8 is a sectional view taken on the plane of the line 3—8 of Fig. 4, looking in the direction of the arrows;

15 Fig. 9 is a sectional view taken on the plane of the line 9—9 of Fig. 4, looking in the direction of the arrows;

Fig. 10 is a sectional view taken on the plane of the line 10—10 of Fig. 1, showing the shield plate and valves.

The present air and liquid nozzle is employed with 20 sources of water under the pressure which is customary in city mains and sources of air under pressure which are available at the points of use, and which may be provided by the usual air compressors which provide air at from 60 to 150 pounds per square inch.

For convenience the nozzle may be employed with a transportation unit having an electric motor driving a gear pump on an upper shelf, a hose reel with the required hose, and a lower shelf supporting a drum filled with detergent solution.

Referring to Fig. 1 10 indicates in its entirety an air and liquid spray gun embodying my invention and adapted to be supplied with liquid through the hose 11 and air through the hose 12, which are connected to the gun unit through shut-off valves 13 and 14.

35 The valves 13 and 14 have their valve handles 15 and 16 provided with pointers 17, 18, indicating that the valves are shut off when the pointer extends transversely. The valve 13 has its body 19 connected to a threaded pipe 21, having a nut 22; and the pipe passes through an aperture 23 in a shield plate 24, comprising a rectangular metal plate for supporting the valves in adjacent position so that the conduits may serve as a handle.

The shield plate 24 is wide enough on the handle side of each valve to project beyond the handle and protect them against breakage. The shield plate 24 has a second aperture 25 for passing the nipple 26, connected to the hose 12, leading to the valve 14; and the plate is provided with a projecting flange 27, extending beyond the valve handle 15 far enough to prevent the handle from engaging anything which might break it when the air and liquid gun is dropped.

50 The valves 13 and 14 are staggered on opposite sides of the shield plate 24 so that they may be close together, with the handles 15 and 16 so mounted that they do not interfere with each other. The valve 14 is connected to a second threaded metal pipe 28; and nipple 26 is provided with a nut 29, clamping the plate 24 against the valve body 14.

Pipe 21 is provided with a threaded nut 22, clamping the plate 24 against the valve body 19. Thus the plate 24 shields and protects the valves and holds the two pipes 21 and 28 in parallel position at their right ends. Pipe 21 is threaded into a threaded bore 30 in the gun housing 31; and pipe 28 is threaded into a threaded bore 32 in the gun housing 31.

60 Bores 30 and 32 each communicate with larger counterbores 33, 34 for receiving the end of the covering hose 35, 36, which extends the full length of the pipes 21 and 28 in each case, protecting the user against heat when hot water is employed, and providing a convenient handle.

The hoses 35 and 36 may be made of neoprene, resisting deterioration by grease.

The gun housing 31 comprises a metal casting preferably made of brass or other non-corrodible material; and the inlet fittings 37 and 38 preferably bear the letters "W" and "A," as shown in Fig. 1, to guide the user in connecting the air and water conduits 11 and 12 to the right nipples.

The inlet fittings 37 and 38 contain the two conduits 39 and 40, which join and communicate with a single conduit 41 located in a cylindrical body 42. The water conduit 39 has a larger threaded bore 43 for receiving a copper water pipe 44, which has a threaded end 45 in the threaded bore 43.

The counterbore 41 is larger than the pipe 44, leaving an annular air space 46, which communicates with the air conduit 40 at its outlet 47. The copper water pipe 44 is adapted to resist attack by detergent solutions or other cleaning solutions or acids that might be employed in solution in the liquid supply pipe 44.

This supply pipe leads to a spray head plug 48 (Fig. 6), having a threaded end 49 to be received in the threaded end 50 of pipe 44. Plug 48 preferably has a projecting knurled portion 51 with an annular shoulder 52 engaging a sealing washer 53 of neoprene; but the sealing washer is not essential, since the other connection may be liquid-tight.

The plug 48 may have a cylindrical body 54 and a central bore 55. The cylindrical body may be provided with a pair of radial flanges 56 and 57, having cylindrical edges, and having a partially circular groove 58 between them.

A neoprene O ring is located in the groove and projects from it sufficiently to effect a liquid-tight seal with the inner cylindrical surface 60 of a spray cap 61. The spray cap 61 has an inner threaded bore 62 of reduced size, which may be threaded on the threaded portion 63 of the plug 48, causing the sealing sleeve portion 64 of the cap 61 to slide back and forth on the O ring 59.

The inner bore 55 in the plug 48 extends to a small bore 65, which communicates with the laterally extending bores 66, of which there are a plurality, such as four, leading to an annular groove 67 surrounding a neck 68 of reduced size.

Except for the radial outlets 66, the bores 65 and 55 are closed at the outlet end by a frusto-conical head 69, having a plane end 70 and a frusto-conical surface 71 provided with spiral grooves 72 open at their rear ends to communicate with the groove 68 behind the head 69 and open at their front ends to communicate with the space surrounding the plane end 70, this space being indicated at 73 in Fig. 4.

The cap 61 has its inner threads 62 longer than the outer threads 63 on the plug 48, permitting the cap to be adjusted beyond the positions shown; and there is a clearance at 74 between the end of the skirt 64 and the annular shoulder 75 on the knurled portion 57 so that the cap 61 can be adjusted until its inner conical surface 76 engages the conical surface 71 on the head 69, closing all of the space 76 except the spiral grooves 72, which are not closed because they extend into the head surface 71.

Cap 61 has a closed end 77 except for a central cylindrical discharge opening 78; and the exterior surface of cap 61 is knurled at 79 for grip with the fingers in adjusting the cap. The exterior of the end wall 77 has a partially spherical surface 80 and a flat end 81 surrounding the nozzle aperture 78.

The annular conduit 46 carries the air and is formed by the bore 41 and continued by an outer cap 82, which has an inner bore 83 of cylindrical shape surrounding the inner cap 61. Bore 83 terminates at an end wall 84, which is provided with an inner frustoconical surface 85 located to engage the partially circular surface 80 on the

inner cap and to regulate the pressure of air passing these surfaces.

There is a space 86 inside the outer cap 82 in advance of the plane end surface 81 of the inner cap 61; and the space 86 communicates with a cylindrical outlet bore 87 larger than the outlet bore 78 of the inner cap, since the outlet 87 of the outer cap 82 must pass both air and water or other liquids.

The outer cap 82 has a smaller cylindrical nose portion 88 communicating with a larger cylindrical skirt portion 89, which has a knurled outer surface 90 for grip by the fingers. The bore 83 in the nose portion 88 communicates with a larger bore 91 in the skirt 89; and the bore 91 has an elongated inner threaded portion 92.

The length of this threaded portion 92 is sufficient to permit the adjustment of the cap 82 on the outer threaded portion 93 of the body 31 to such a point that air is cut off between the surfaces 80 and 85 on the inner cap and the inside of the outer cap. As a general rule, the outer cap 82 will be adjusted to such a point that there is a restricted opening between 80 and 85, reducing the pressure of the air passing through this annular space so that the air pressure in the space 86 approximates the pressure of the water or detergent solution coming out of the discharge aperture 78 of the inner nozzle cap to prevent the air from stopping the flow of the liquid.

The operation of the air and liquid spray gun is as follows: The liquid conduit 11, labeled "W" on the gun, is connected to a supply of detergent solution under pressure, which is supplied by the water pipes from the city main at water pressure of from 30 to 90 pounds per square inch.

The air pipe 12 is connected to the local air compressor driven by a motor or connected to the usual air compressor tank, providing air at pressures of from 60 to 150 pounds per square inch.

The inner cap 61 is adjusted so that it provides a suitable conical spray of liquid, such as detergent; and the outer cap 82 is so adjusted that the air entrains and carries forward the sprayed detergent and provides it with sufficient force to impact the areas of the diesel engine to be cleaned. The detergent emulsifies the grease and oil; and the combined air and detergent clean off the engine surfaces, the dirt and emulsified grease falling in the pit.

Thereafter the pipe 11 is connected to the water supply under the same pressure; and the engine is forcibly sprayed with air and water. The water washes away all remaining detergent and dirt and, because of the use of a sufficient amount of air, leaves the engine dry.

Whereas two or three hours were formerly required to clean a diesel engine with 25 to 50 gallons of water, when the present air and liquid gun is employed, the use of water is reduced to about 5 gallons; and the time consumed may be 30 minutes.

It will thus be observed that I have invented an improved air and liquid spray gun particularly adapted to be used in cleaning greasy and dirty surfaces, such as those on diesel engines of locomotives; and this spray gun may be employed with widely different air and water pressures without the air stopping the flow of the water.

The air entrains and drives the liquid spray from the gun with sufficient force to clean the surfaces in a minimum amount of time; and the present gun may be adjusted to utilize any of the existing air and water pressures.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In a combined air and liquid spray gun for clean-

ing greasy surfaces, a gun housing having a pair of inlet fittings surrounding two inwardly threaded conduits, a pair of metal pipes, each having one end threaded into one of said threaded conduits, and each having threaded fittings at their opposite ends, and each of the latter threaded fittings supporting a valve provided with a laterally projecting handle, a substantially rectangular shield plate having a pair of apertures in alignment with said pipes, the said latter fittings passing through said apertures, and having threaded nuts clamping the shield plate with the valves on opposite sides of the shield plate, the said shield plate being of sufficient size to have its edges projecting beyond the valves and valve handles to prevent anything from engaging the handles when the spray gun is dropped, said gun housing having an obtuse bend in its liquid conduit, which is provided with an enlarged counterbore communicating with said air inlet conduit, and said liquid conduit being internally threaded and provided with a metal liquid pipe defining an annular air space in said counterbore communicating with the air conduit, the said liquid pipe being provided with internal threads, having a spray head plug threaded therein and forming a continuation thereof, said spray head plug having an inner bore leading to a small bore terminating at a closed end, said small bore communicating with lateral bores leading to an annular groove and said plug having a frusto-conical head, said head having a plane end surface and a frusto-conical surface which is provided with spiral grooves opening at their front ends at said plane end surface and communicating at their rear ends with said annular groove in the plug, the said plug having a threaded portion adjacent said annular groove, an inner spray cap having inner threads engaging the threaded portion of said plug, said plug having a pair of radial flanges with a partially circular groove between them, a resilient O ring located in the latter groove and projecting from it slightly to effect a seal with an inner cylindrical surface of said spray cap, said spray cap having a sealing sleeve portion sliding back and forth on the

 O ring as the cap progresses on said plug threads, said cap having a bore larger than said frusto-conical head beyond its threads, and having an inner frusto-conical surface opposing the frusto-conical surface on said plug, said cap having a centrally located cylindrical discharge opening for passing a whirling spray coming from said spiral grooves, the said cap terminating at its end in an outer partially cylindrical annular surface, an outer cap comprising a cylindrical member having an inner bore of cylindrical shape surrounding the inner cap and terminating at an end wall provided with an inner frusto-conical surface to engage the partially spherical surface on the inner cap, said outer cap having a cylindrical outlet bore in its end which is larger than the outlet bore of
 10 the inner cap for passing both air and liquid, said outer cap having an open internally threaded end provided with a larger bore adapted to be threaded on the body of the spray gun and adjusted to the point of closing or throttling the passage of air between the inner cap and the outer cap.
 15 20 2. A combined air and liquid spray gun according to claim 1, in which the air and liquid inlets of the gun housing have enlarged counterbores outwardly of their threads surrounding the metal pipes and the metal pipes are covered with the rubber hose extending into and confined in said latter counterbore.
